UNITED STATES PATENT OFFICE

WILLIAM ERASTUS WILLIAMS, OF WILMETTE, ILLINOIS, ASSIGNOR TO DITTO, INCORPORATED, OF CHICAGO, ILLINOIS, A CORPORATION OF WEST VIRGINIA

GELATIN-SHEET COPYING MACHINE

Application filed July 23, 1928. Serial No. 294,608.

My invention relates to those machines which make copies by the hectograph principle using a gelatin coated sheet which is wound upon a spindle at one end of the machine and trained over a bed and wound upon another spindle at the other end of the machine and an impression carriage is mounted to travel backward and forward over the impression bed and carry a platen roll adapted to impress paper onto a gelatin sheet and thereby make copies in the hectograph way.

The object of the invention is to make a machine with an improved type of impression carriage wherein the platen roll is revolved positively all the time in the travel of the carriage over the bed and another object of the invention is to so mount the carriage that it will travel easily backward and forward in impressing the paper on the bed and will be held squarely in all positions of its travel. Another object of the invention is to provide means for so placing the impression carriage that free access may be had to the gelatin sheet in introducing a new sheet or in cleaning and preparing the gelatin for service.

Another object of the invention is to provide winding mechanism that will permit the gelatin sheet to be wound with facility in either direction from either spindle at either end of the machine as desired.

Other objects of the invention are shown in detail of construction that will be set forth herein.

Reference will be had to the accompanying drawings in which Fig. 1 is a side elevation of the machine being what is termed the left side of the machine since the operator is positioned at the right end of the machine as shown in Fig. 1.

Fig. 2 is a vertical sectional elevation of the machine looking in the same direction as that of Fig. 1 but on line 2—2 of Fig. 4.

Fig. 3 is a transverse detail of a stop block adapted and used to limit the outward travel of the carriage.

Fig. 4 is a plan view of the machine.

Fig. 5 is a sectional elevation looking from the right side of the machine being the opposite side from which the views Figs. 1 and 2

are taken and shows a section of the carriage and a portion of the front of the machine.

Fig. 6 is a detail showing the trunnion bearings for the trunnions of the rocker shaft which carries the platen roll.

Fig. 7 is a view looking from the same direction and the parts in substantially the same position as that of Fig. 5 but showing the outside or right side of the impression carriage.

Fig. 8 is a similar view to that of Fig. 5 but with the impression carriage moved down to the position where a new gelatin sheet roll is to be applied onto the machine. This view is looking on the opposite side from what is shown in Figs. 1 and 2.

Fig. 9 is a plan detail of the right end of the platen roll shaft and the rocker shaft which carries the platen roll.

Fig. 10 is a vertical section on line 10—10 of Fig. 9 but there is added in Fig. 10 a support bearing for the rocker shaft which supports the platen roll.

Fig. 11 is a front elevation of the machine being the end nearest to the operator being the right end of the Figs. 1 and 2 but in Fig. 11 a part of the impression carriage is omitted.

Fig. 12 is a transverse section through the frame of the machine on line 12—12 of Fig. 4.

Fig. 13 is a plan of the right or front end of the frame of the machine illustrating the mechanism which controls the stops against which the carriage registers at the commencement of making copies.

Fig. 14 on same sheet as that of Fig. 8 is a plan of the ratchet connection which holds the rocker shaft which carries the platen roll down in service position.

In the drawings 1 indicates the legs or feet which support the machine from a table or stand and 2 indicates the left side frame member and 3 the right side frame member of the body of the machine. These side frame members 2 and 3 are preferably made out of castings and they are tied across at their bases by the cross-beams or girders 4 secured by screws 5 and at the top of the machine there are the cross-beams 6 of angular form reinforced by the supplemental angular pieces 7 which sup-

port the ends of a bed plate 8 which is covered on the top, as desired, by a layer of felt 9 or other blanket material terminating in a marginal flange 10 around the entire bed plate 8 (see Figs. 2, 3 and 4) and the bed plate 8 is fastened to the side frame members through the medium of screws 11 screwed into an angle bar 12 which extends horizontally on the inside of the side frame 2 and is secured thereto by screws or rivets through the medium of little angle blocks 13 fastened by screws 14 in the side frame members (see Fig. 12). Thus the side frame members are bound across at the top by the cross-beams 6 and 7 and the bed plate 8. On each side of the side frames on the top outer edge there are rails or bars 15 secured by screws 16 to the side frame members. At the front end of the machine being the right of Figs. 1 and 2 there are curved end segmental plates 17 and the top edges of the bars 15 and the segmental plates 17 furnish the trackways upon which the impression carriage rides. The side frame members 2 and 3 are provided with rack teeth 18 shown in dotted lines in Fig. 8 which are cut through at the bases of the teeth leaving a clear passageway between each tooth into the offset spaces 19 (see Figs. 3 or 12) the rack teeth being integral with the portion 20 of the side frames. At the front end of the machine the rack teeth are extended down over the curved ends of the side frames as indicated by Fig. 8. The open space 19 at the base of the rack teeth permits any foreign matter to pass down through the teeth, thus at all times leaving the rack teeth clear to be engaged by the carriage gears. The main body of the side frames 2 and 3 being the bed portions of the frames have on their insides the space 21 at the left side of the frame 2 of the machine and space 22 on the right side frame 3. The space 21 is closed by a plate 23 (see Fig. 12).

The plate 23 together with the outer wall of the side frame 2 furnishes the bearings for gudgeon shafts 24 and 25 (see Figs. 1 and 4). These gudgeon shafts engage the gudgeon blocks 26 of the roll spindles 27 upon which the gelatin sheet 28 is wound. At the right side of the machine the ends of the spindles 27 are held by little trunnions 29 (see Fig. 12) which are on the ends of the gudgeons 26 of the roll spindles 27 and these trunnion ends 29 are supported in blocks 30 secured into a spring bar 31 at the front of the machine and a spring bar 32 at the rear of the machine. These bars are fastened by screws 33 to the right frame piece 3 of the machine (see Fig. 2). Beveled notches 34 shown in full lines in Fig. 2 and in dotted lines in Fig. 12 direct the trunnions 29 to enter little holes adapted to carry the said trunnions and thus support the right ends of the spindles. The spring bars 31 and 32 allow the blocks 30 to be sprung toward the right of Fig. 12 and thus

release the gudgeon ends 26 from the gudgeon shafts 24 and 25 in taking out and putting in a new spindle.

The gudgeon shafts 24 and 25 are driven through the medium of a handwheel 35 (see Figs. 1 and 4) upon a shaft 36 which shaft 36 is supported in a bearing 37 in a block 38 shown in dotted lines in Fig. 1 the block 38 being hinged on a hinge pin 39 which passes through the outer wall of the side frame member 2 and through the plate 23. The block 38 is supported in the spaces 21 between the wall of the side frame 2 and the plate 23. The lower end of the block 39 is in the form of an arm 40 which is connected at 41 to a link 42 hinged to a rocker shaft lever 43 hinged to a short shaft 44 in the side frame 2. Outside of the side frame 2 on the shaft 44 there is a lever 45 having a hand hold knob 46 which permits the operator to rock the lever 43 from the position of Fig. 1 over to the right, thus swinging the block 38 carrying the hand wheel 35 with it over toward the right of Fig. 1. Upon the gudgeon shaft 24 there is a gear 47 and on the shaft 36 there is a gear 48 and when the block 38 is thrown far enough to the right of Fig. 1 the gear 48 meshes with and drives the gear 47 and the gudgeon shaft 24 and thus winds or unwinds the spindle carrying the gelatin sheet roll 95 at the front of the machine. A gear 49 on a shaft 50 is supported in the space 21 and on this shaft 50 there is a sprocket wheel which offsets from the gear 49 and fastened thereto and upon which there is mounted a chain 51 and when the parts are in the position shown in Fig. 1 the gear 48 is in engagement with the gear 49 and thus a revolution of the hand wheel 35 will drive the chain 51. But on the turning of the bell crank lever 45 by the handle knob 46 over toward the right the gear 48 is released from the gear 49 and thrown into engagement with the gear 47 on the gudgeon shaft 24. The side frame member 2 is slotted to permit the bearing 37 to extend through the side frame 2 to permit this movement of the shaft 37 for engagement of either gear 47 or gear 49 as desired.

On the gudgeon shaft 24 there is alongside the gear 47 a ratchet 52 and a pawl 53 hinged at 54 engaging the ratchet 52 to prevent its revolution in a backward direction the pawl 53 having a weighted end 55 which automatically holds the pawl 53 in place. A little rocker shaft 56 has mounted upon it a small block 57 adapted to lift the weighted end 55 of the pawl 53 and hold it out of engagement when it is desired to unwind the spindle under control of the gudgeon shaft 24. The small hand knob 58 permits the operator to control the movement of the shaft 56 with its block 57. At the outer end or the left side of Fig. 1 the gudgeon shaft 25 has mounted upon it a ratchet 59 which is engaged by the pawl 60 in a similar manner to that of 130

the ratchet 52 at the front of the machine but the pawl 60 is disengaged from the ratchet 59 by a pin in the end of a link 61 extending back toward the front on the inside of the plate 23 and hinged at 62 to a little lever 63 likewise on the inside of plate 23 to a shaft 64 on the side of the side frame member 2 and having fixed thereon a lever 65 which has a hand hold knob 66 by which the operator may move the bar 61 to disengage the pawl 60 but when the pawl is in engagement with the ratchet 59 the bar 61 is out of contact with the pawl 60 to permit it to function normally as an automatic pawl to prevent the gudgeon shaft 25 from revolving save only in one direction.

Alongside of the ratchet 59 there is a gear 67 which is in the position of Fig. 1 engaged by the gear 68 on a shaft 69 which shaft 69 is carried by a block 70 hinged at 71 in the side frame member 2 and the block 70 is connected at 72 to a link 73 which extends toward the front of the machine and is connected at 74 to rocker shaft block 43, before mentioned, so that on a movement of the hand knob 46 the rocker shaft block 43 moves the block 70 carrying the shaft 69 with its gear 68 to a position out of engagement with the gear 67 on the gudgeon shaft 25 and thus disengage the driving of the gudgeon shaft from the hand wheel 35 but in the position of the parts shown in Fig. 1 the hand wheel as connected up will revolve the shaft 25 since the chain 51 passes over a sprocket 75 on the shaft 69 and drives gear 68.

Thus when the gudgeon shaft 24 is revolved by the hand wheel 35 the gudgeon 25 is released from any connection to be driven by the hand wheel 35. Thus by the one hand wheel the gudgeon shaft 24 or the gudgeon shaft 25 may alternately be revolved to suit the operator whenever he sees fit to shift the position of the shaft 36 through the medium of the knob 46 and the gelatin sheet thus may be drawn and wound to or from either spindle 27 at the front or the rear of the machine and drawn over the impression bed 8 as desired.

The impression carriage is provided with a side plate 76 at the left side of the machine 50 and a side plate 77 at the right side which plates are connected across by a girder plate 78 having a stiffening flange 79. The girder plate 78 also acting as a paper guide to direct the paper down to the proper position for 55 registration on the impression bed. The side plates 76 and 77 are also connected across at the front of the carriage by a rod 80 passing through little brackets 81 on the side plates of the carriage. The carriage is supported on idle rollers 82 on a shaft 83 at the rear of the carriage and idle rollers 84 on a shaft 85 at the front of the machine (see Figs. 1, 5 and 8). The shaft 83 is held in roller bearings 86 (see Fig. 7), while the shaft 85 is held in roller bearing 87 (see Figs.

5 and 8) in peculiarly shaped blocks 88 which are supported in dove-tailed grooves in the side plates 76 and 77 and the blocks 88 are integral with the curved and peculiarly shaped portion 90 which extends in the same vertical plane as the side plates of the carriage and extend back and connected at 91 to arms 92 fixed on a rocker shaft 93 mounted in bearings in the side plates of the carriage. The rocker shaft 93 is provided with an arm 94 (see Figs. 2, 4 and 7) connected at 95 to a screw threaded rod 96 passing through the girder 78 of the carriage and is provided with a thumb nut 97 for adjusting the movement of the rocker shaft 93 to move the blocks 88 which carry the shaft 85 and thus move horizontally the shaft 85 in relation to the body of the impression carriage, this movement being controlled by the thumb nut 97. A jam thumb nut 98 locks the thumb nut 97 from accidental movement.

The rollers 82 and 84 revolve idle on the shafts 83 and 85 and ride on the rail bars 15. Mounted adjacent to the rollers 82 on the shaft 83 and fixed to the said shaft are gear wheels 99 one at each side frame of the carriage and these gears 99 are engaged by rack teeth 18 before described and since the gears 99 are fixed on a shaft 83 the carriage thus is held squarely to the frame of the machine in any movement backward and forward of the gears on their respective racks. On the shaft 85 and adjacent to the rollers 84 there are gear wheels 100 fixed to the said shaft 85 arranged to travel positively by engagement with the rack teeth 18 in a similar manner to the gears 99 notwithstanding the fact that the shaft 85 may be adjusted to or from the shaft 83 by means of the rocker shaft 93 before mentioned.

At the outer right end of the shaft 85 (see Fig. 4) there is mounted a flanged pulley wheel 101 which pulley wheel revolves positively with the shaft 85 and it, in turn, under the control of the gear wheels 100, so that as the carriage is moved outward and backward over the impression bed 8 the flanged pulley 101 revolves positively in either direction as the carriage moves.

At the right side of the impression carriage there extends out over the side plate 77 a bracket bar 102 which bar is fixed to the side plate 77 by means of an angle block 103 (see Fig. 11) at the top of the side plate 77 and is connected at the lower edge of the plate 77 by the screws 104. Stud shafts 105 and 106 (see Fig. 7) extend through the bracket 102 and into the side plate 77 and furnish bearings for the flanged idle pulleys 107 and 108. A belt 109 is trained over the pulley 101 and in between the idle pulleys 107 and 108 and passes over a pulley 110 on the shaft 111 of a platen roll 112 the latter being the rubber faced roll which impresses the paper onto the portion of the gelatin sheet 113 that is on

the impression bed 8. Thus as the carriage is moved backward and forward over the bed a positive revolution of the shaft 85 drives positively the rubber faced platen roll 112. The shaft 111 of the said platen roll 112 at the right side of the carriage is supported at the right side of the machine by a peculiarly shaped arm 114 carried on a rocker shaft 115 (see Fig. 9) which shaft 115 is provided with trunnions 116 by which it is supported in the frame of the carriage and on these trunnions the rocker shaft 115 raises and lowers the platen roll 112 as shown by full line position and dotted line position as indicated in Figs. 5 and 7. Thus by reference to Fig. 7 it will be seen that the position of the trunnion center 116 is substantially the position whereat the belt 109 on each side passes in between the idle pulleys 107 and 108 over this trunnion center 116 of shaft 115, so that regardless of whatever position the platen roll may be in in relation to the impression bed 8 and gelatin pad 113 thereon the platen roll 112 itself will not be moved by the belt 109 in a revolving motion by the oscillation of the rocker shaft 115 in raising and lowering the platen roll 112 to and from the gelatin, but the platen roll will be positively moved by the belt 109 as the carriage is moved backward and forward over the bed of the machine.

The bracket 102 has an extension 117 (see Figs. 2, 6 10 and 11) which extends on the inside of the side plates of the carriage downward to furnish the bearing for the right end of the rocker shaft 115. This bearing is notched out on one side (see Figs. 6 and 10) and covered by sliding block 118 secured by the screws into the projection 117 and passing through slots in the block 118 thus the block 118 may be raised on the uncovering of one side of the bearing and permitting the removal of the shaft 115. A bracket 119 at the left side of the carriage is secured by the angle block 120 (see Fig. 11) to the side plate 76 in the same manner as the bracket 102 is fixed to the side plate 77. This bracket 119 extends down in a projection 121 to furnish the bearing for the left end of the shaft 115 in the same manner as the projection 117 for the right end of the shaft 115 and a similar block to that of block 118 is also provided for this projection 121; thus the shaft 115 carrying the platen roll 112 may be taken out in toto by lifting the blocks 118 to free the trunnions 116 from supporting bearings in projections 117 and 121.

The platen roller 112 may be released from the arm 114 (see Figs. 9 and 10) due to the fact that the bearing from the shaft 111 of the roller in the arm 114 is open at the bottom and the shaft 111 is held in place by latch hook 122 hinged at 123 and held by spring 124 to hold the latch in an engaging position to hold the shaft 111 in place in the

bearing in the arm 114. A projection 125 on the latch 122 permits the operator to release the latch hook and permit the shaft 111 of the platen roller 112 to drop out from engagement with the arm 114.

The other end or the left end of the platen roller 112 is held in an arm 126 on the shaft 115 (see Figs. 4, 5, and 8). The arms 114 and 126 are mounted on shaft 115 by their hubs 127 for the arm 114 and 128 for the arm 126. These hubs are provided with up-standing projections 129 at the right of the machine and 130 at the left of the machine and these projections 129 and 130 are engaged by pins 131 and 132 (see Figs. 5 and 10) which pass through holes 133 in the projections 129 and 130 which holes are slightly larger than the pins 131 and 132 and the pins 131 and 132 are secured in the blocks 134 and 135 the block 134 being a relatively short block while block 135 extends higher than the block 134 and is provided with a ratchet block 136 (see Figs. 8 and 11) which block is secured by screws 137 to the aforementioned block 135. The arrangement of the pins 131 and 132 and the holes 133 is such that the arms 114 and 126 which carry the impression or platen rubber faced roller 112 may have a slight rocking motion in relation to their fixture to the rocker shaft 115 to permit the platen roll 112 to adjust itself on either end to fit any irregularity in the thickness of the gelatin sheet portion 113 on the impression bed 8 or any variation in the thickness of the paper copy to be applied thereon and this adjustment is made by an elastic pressure through the medium of springs 138 (see Fig. 10) coiled on the shaft 115 and secured into the hubs 127 and 128 of the arms 114 and 126 and at the other side of these springs into collars 129 which are provided with ratchet teeth 140 adapted to be adjusted and engage similar teeth on similar collars 141 fixed to shaft 115 whereat the tightening action or loosening of the springs 138 may be brought about by the adjustment of the collars 139.

The springs 138 and the collars 139 and 141 normally are concealed by slip covers in the form of a short piece of tubing which slides over and covers up the said parts, this tubing being indicated by 142 in Fig. 4.

The ratchet block 136 is provided with ratchet teeth 143 (see Fig. 14) extending horizontally to the left of the machine and these teeth are engaged whenever the platen roller is down in the service position by corresponding teeth in a sliding block 144 mounted in dove-tailed groove in the bracket 119 and provided with thumb knob 145 which knob has a projection which extends down through a slot in the bracket 119 (see Fig. 11) which projection is connected to a spring 146 in a manner to push the block 144 to the right in Fig. 11 and thus engage the ratchet block 136.

136 and hold the same whenever the platen roll is in service position in laying on the paper on the gelatin sheet. At the outer end or left end of the block 144 and on the lower edge thereof there is a small roller 147 which 5 is engaged by a beveled edge 148 of a lever 149 hinged at 150 (see Fig. 1) to the left side plate 76 of the carriage and this lever 149 has a pin 151 which extends through a slot in the side plate 76 and is adapted to be engaged by a stop bar 152 when the carriage 10 is home or at the right end of the machine when the pin 151 will hit the bar 152 and thus move the lever 149 to cause its cam or beveled surface 148 to act on the roller 147 of the block 144 to release the ratchet block 136 to permit the rocker shaft 115 to be raised and thus raise the platen roll 112. The thumb 15 knob 145 permits this release of the ratchet teeth whenever the operator so desires.

22 The rocker shaft 115 is actuated by an arm 153 upon which is mounted a handle hold bulb 154.

Hinged at 155 in the side frames 2 and 3 25 of the machine are arms 156 which are connected to and support a standard margin bar 157 (see Fig. 5) which margin bar has a shoulder 158 against which the paper is abutted and thus registered on its entrance 30 to the machine for copying purposes, the paper being indicated by 159. Whenever a new spindle carrying the end of a new gelatin pad sheet is desired to be entered into the machine, the margin bar 157 is revolved to 35 the position of Fig. 8 and is held in repose in that position by a stop 160 but in the normal service of the machine the margin bar is in the position of Fig. 5. A clamping roll 161 (see Figs. 2, 4, 5, 7 and 8) adapted 40 to clamp paper to the platen roll 112 is mounted in arms 162 hinged at 163 to bearing blocks 164 secured to the cross frame girders 78. The arms 162 are provided with extensions 165 in the end of which there are 45 set screws 166 which bear on the cross girder 78 and limit in one direction the movement of the arms 162.

Eye-bolts 167 are connected to the extensions 165 at 168 and project through the 50 girder 78 and are provided with springs 169 and nuts 170 by which the springs 169 may be adjusted to bring the compression roller in suitable contact with the platen roll 112 in the act of laying down and taking up the 55 paper from the gelatin sheet.

A lateral or side paper guide (see Fig. 4) for directing the paper to side registration is provided in the form of a plate 171 having the side flange 172 and a turned over flange 60 173 secured and adjusted by a thumb nut bolt 174 adapted to slide along a slot 175 in the flange 79 of the cross girder 78. Thus the inside guide flange 172 may be moved for any edge or side guide for the paper sheet 159. 65 The carriage is provided with stop blocks on

each side, the one on the left side which is secured on the inside of the side plate 76 of the carriage is shown in dotted lines in Fig. 1 and is indicated by 176 and is secured to the side plate by a bolt 177 and a rivet 178. This block 176 on the left side of the machine is apertured at 179 to permit the entrance of the pin 151 when the same is moved backward when the carriage moves to contact with the stop bar 152. Thus this aperture 179 allows the block 176 to abut against the stop bar 152 on the final shock of stopping the carriage on its movement to home position. On the right side of the machine on the inside of the carriage side plate 77 there is a similar stop 70 block shown in dotted lines in Fig. 7 and indicated by 180 and this likewise is secured to the side plate 77 by a bolt 181 and a rivet 182 and this block abuts against the stop bar 183 which corresponds on the right side to the bar 75 152 on the left side. Thus when the carriage is brought to registering position for the paper for the placement into the machine the blocks 176 and 180 abut against the stop bars 80 152 and 183. These stop bars 152 and 183 90 are best observed in Fig. 13 and they extend through slots in the right and left side frames 2 and 3 of the machine and are Z-bar shaped in general plan view and extend back under the bed of the machine and are secured by 95 screws 184 and 185 to companion bars 186 and 187 which bars 186 and 187 are held together in sliding contact by screws 188 and 189 passing through slots in their opposite 100 companions and are adjustable to and from the side frames to push out or withdraw the stop bars 152 and 183 as desired and the means for moving the bars 186 and 187 and correspondingly the stop bars 152 and 183 are 105 provided in the form of connecting rods 190 and 191 hinged at 192 and 193 with small angle blocks secured respectively to the bars 186 and 187 and the rods 190 and 191 are hinged at their other ends at 194 and 195 to a lever block 196 hinged on a pin 197 (see also 110 Fig. 5) which pin 197 is secured by a bracket 198 to the side frame member 2. The lever block 196 has a hand hold projection 199 (see Figs. 1 and 13) extending outside of the left frame member 2 to permit the operator to move the stop bars 152 and 183 outward to engage and stop the carriage to registering position and allow the carriage to pass by the stop bars and roll down from the position of 115 Fig. 5 to the position of Fig. 8 the gear wheels riding into the rack teeth on the curved end of the side frame. The carriage is held from falling off from the frame by reason of two small rollers 200, one on each side mounted on the bolt 177 and the bolt 181 and are best 120 observed in Figs. 7 and 8. These rollers bear on the under side of the rail bars 15 and thus normally hold the carriage into the frame at all times. When the carriage is turned to the 125 position of Fig. 8 the rollers 200 ride onto the 130

edges 201 of the curved end plates 17 at the right end of the carriage. The purpose of moving the carriage from the position of Fig. 7 to that of Fig. 8 is to provide clearance space between the end of the bed 8 and the back end of the carriage to allow the spindle of a fresh roll to be entered to the position at the front end of the machine.

In order to allow a new spindle to be entered and an old one to be removed the margin bar 157 must be moved from the position shown in Fig. 5 to that shown in Fig. 8 and for convenience in moving this margin bar and in saving the time of the operator, I connect it up to be moved by the hand hold projection 199 of the lever block 196 and this connection is best shown in Figs. 2 and 13 and is brought about by the rod 202 connected also at the point 195 to the block 196 and at the other end at 203 to a bell crank lever 204 hinged at 205 to a block 206 secured at 207 to the right frame 3 of the machine. The bell crank lever 204 is connected at 208 to a small rod 209 connected at 210 to a rack block 211 engaging a pinion 212 fixed on the right arm 156 of the margin bar 157. Thus when the lever block 196 is moved withdrawing the stop bars 152 and 183 inwardly to clear the stop blocks 176 and 180 simultaneously the margin bar 157 is rocked to the position of Fig. 8 through the medium of rack 211 and pinion 212 connected as described.

Some operators may prefer to catch hold directly of the margin bar 157 and rock it over from the position of Fig. 5 to that of Fig. 8 and since it is connected by the rack and pinion as described, it will likewise move and retract the stop bars 152 and 183 thus making, as it were, as purely a matter of convenience the use of the hand hold projection 199 of the block 196.

In the operation of the machine the rocker shaft 115 is moved by the hand hold bulb 154 raising and lowering the platen roll 112. The amount of this movement is indicated in dotted lines in Fig. 5 and is limited by the stop pins 213 and 214 fixed to a segment 215 fixed to the projection 121 of the bracket 119 at the left side of the carriage.

As before stated the belt 109 positively drives the rubber faced platen roll 112 due to the pulley 101 being fixed to the shaft 85 driven positively by the gear wheels 100 engaging the rack teeth on the side frame as before described. However, in order to apply the belt 109 in the first place and hold it taut in its operation the shaft 85 with its gears 100 is made adjustable for belt tightening purposes through the means of the rocker shaft 93 its arms 92 and the portion 90 of the blocks 88. Thus by the adjustment of the rod 96 by the thumb nut 97 and its thumb jam nut 98 the belt 109 may be loosened or tightened as desired.

In place of the belt 109 I may use any flex-

ible connection such as a sprocket chain or any other suitable substitute for a belt, the point being to train the belt members closely together over the center of the trunnions 116 of the rocker shaft 115 and thus making a pivot, as it were, about which hinged center the portions of the belt will rock in the raising and lowering of the platen roll 112 without bringing about a revolving action of the said roll.

It is necessary to prevent the platen roll from revolving in laying down to first contact the paper to the gelatin sheet as in doing this if the platen roll revolves it displaces the register against the shoulder 158 of the margin bar 157.

The arrangement of the mounting of the carriage on the frame whereby the carriage may be pulled down over the end of the side frame as shown by Fig. 8 is a handy arrangement for making clearance to enter a fresh spindle and remove the used one and at the same time to give free access to the gelatin sheet 113 located upon the impression bed 8.

What I claim is:

1. In a machine of the class described, a frame adapted to have mounted therein spindles carrying gelatin sheet rolls and an impression bed over which said sheet is trained for the exposure of the gelatin for copying purposes, rack teeth on each side of the said bed, and trackways associated with the said rack teeth and said rack teeth and trackways merging into a downward curved portion at the front of the machine, an impression carriage mounted on the said trackways and adapted to be moved outward and back over the said impression bed, and downwardly over the downward curved portion of said frame, gears on the said carriage on the said impression bed and engaged by the said rack teeth on the said frame.

2. In a machine of the class described, a frame adapted to have mounted therein spindles carrying gelatin sheet rolls and an impression bed over which said sheet is trained for the exposure of the gelatin for copying purposes, rack teeth on each side of the said bed, and trackways associated with the said rack teeth and said rack teeth and trackways merging into a downward curved portion at the front of the machine, an impression carriage mounted on the said trackways and adapted to be moved outward and back over the said impression bed and carrying gears engaged by the said rack teeth on the said frame, an adjustable stop for limiting the movement of the said carriage to a registering position for placing paper to be copied onto the gelatin sheet on the said bed and means for adjusting the said stop to clear the passage for the said impression carriage permitting it to be moved downward onto the said downward curved portion of the said rack.

3. In a machine of the class described, a

frame provided with an impression bed, a gelatin sheet trained over the said bed, trackways on each side of the said bed adapted to carry an impression carriage, rack teeth disposed along each side of said bed, an impression carriage mounted on the said trackways and provided with a pair of spaced cross shafts extending across the said bed each having gears fixed thereon adapted to engage the said rack teeth on each side of the said bed, a platen roller carried by the said carriage and adapted to impress paper onto the gelatin sheet on the said bed, and means for revolving the said platen roll independently of its contact with the said bed and gelatin sheet thereon.

4. In a machine of the class described, a frame provided with an impression bed, a gelatin sheet trained over the said bed, rack teeth on each side of the said bed adapted to carry an impression carriage, an impression carriage mounted on the said trackways and provided with a cross shaft extending across the said bed and having gears fixed thereon adapted to engage the said rack teeth on each side of the said bed, and means for revolving the said platen roll independently of its contact with the said bed and gelatin sheet thereon, said means for revolving the said platen roll driven by the said gears which in turn are driven by the said rack teeth as the said carriage is moved along the said rack.

5. In a machine of the class described, an impression bed adapted to support a gelatin sheet for copying purposes, racks located on each side of the said bed, an impression carriage mounted to be moved outward and back over the said bed and provided with a cross shaft extending from side to side of the said bed and provided with gears fixed thereon and adapted to be engaged by the said racks, and thus guide the carriage squarely in its movement outward and back over the said bed, a platen roller carried by the said carriage and adapted to impress paper on the said bed, a secondary shaft extending across and over the said bed and mounted in the said carriage and having gears fixed on the said secondary shaft and adapted to be engaged by the said racks, said secondary shaft mounted in the said carriage by adjustable means adapted to adjust the position of the said secondary shaft nearer to or further away from the said platen roll, a pulley on the said platen roll shaft and a pulley on the said secondary shaft and a belt trained over the two said pulleys and adapted to drive the said platen roll or hold it stationary as relates to the revolution of the pulley on the said secondary shaft the latter movement being controlled by the said rack teeth and gears on the said secondary shaft and idle pulleys located between the pulley on the said platen roll shaft and the pulley on the said secondary shaft and said idle pulleys adapted to hold the said belt in its travel to cause it to pass closely over the hinge center of the rocker shaft upon which the said platen roll is mounted, a rocker shaft in which the said platen roll is mounted, and hinged into the said carriage and adapted to raise and lower the said platen roll to and from contact with the said gelatin sheet on the said impression bed.

6. In a machine of the class described, an impression bed, racks on each side of the said impression bed, an impression carriage adapted to be mounted and moved outward and back over the said bed, a platen roll mounted in the said carriage and adapted to be raised and lowered in relation to the said bed through the medium of a rocker shaft, a rocker shaft hinged in the said carriage adapted to raise and lower the said platen roll, gearing carried by the said carriage and adapted to be revolved as the said carriage is moved outward and back over the said bed, a pulley on the shaft of the said platen roll, idle pulleys located closely adjacent to the axis center line of the hinge of the said rocker shaft, a pulley adapted to be driven by the said gearing and a belt trained over the last named pulley and between the two said idle pulleys and over the said pulley on the said platen roll, means for adjusting the said pulley driven by the said gearing for tightening the said belt.

7. In a machine of the class described, an impression bed adapted to support a gelatin sheet for copying purposes, racks located on

each side of the said bed, an impression carriage mounted to be moved outward and back over the said bed and provided with a cross shaft extending from side to side of the said bed and provided with gears fixed thereon and adapted to be engaged by the said racks, and thus guide the carriage squarely in its movement outward and back over the said bed, a platen roller carried by the said carriage and adapted to impress paper on the said bed, a secondary shaft extending across and over the said bed and mounted in the said carriage and having gears fixed on the said secondary shaft and adapted to be engaged by the said racks, said secondary shaft mounted in the said carriage by adjustable means adapted to adjust the position of the said secondary shaft nearer to or further away from the said platen roll, a pulley on the said platen roll shaft and a pulley on the said secondary shaft and a belt trained over the two said pulleys and adapted to drive the said platen roll or hold it stationary as relates to the revolution of the pulley on the said secondary shaft the latter movement being controlled by the said rack teeth and gears on the said secondary shaft and idle pulleys located between the pulley on the said platen roll shaft and the pulley on the said secondary shaft and said idle pulleys adapted to hold the said belt in its travel to cause it to pass closely over the hinge center of the rocker shaft upon which the said platen roll is mounted, a rocker shaft in which the said platen roll is mounted, and hinged into the said carriage and adapted to raise and lower the said platen roll to and from contact with the said gelatin sheet on the said impression bed.

8. In a machine of the class described, an impression bed, a rack mounted along the said bed, an impression carriage mounted to

be moved outward and back over the said bed, a gear mounted on a shaft carried by the said impression carriage and the shaft of the said gear adjustable in the said carriage in a line longitudinal of the said bed, 5 a platen roll adapted to impress paper on the said bed, said platen roll mounted in a rocker shaft hinged in the frame of the said carriage adapted to be raised and lowered in relation to the said bed, a pulley on the shaft 10 of the said platen roll and a pulley on the said shaft carrying the said gear and a belt for driving the said platen roll from the said pulley driven by the said gear in connection with the said rack.

15 9. In a machine of the class described, an impression bed, a rack mounted along the said bed, an impression carriage mounted to be moved outward and back over the said bed, a gear mounted on a shaft carried by the said impression carriage and the shaft of the said gear adjustable in the said carriage in a line longitudinal of the said bed, 20 a platen roll adapted to impress paper on the said bed, said platen roll mounted in a rocker shaft hinged in the frame of the said carriage adapted to be raised and lowered in relation to the said bed, a pulley on the shaft of the said platen roll and a pulley on 25 the said shaft carrying the said gear and a belt for driving the said platen roll from the said pulley driven by the said gear in connection with the said rack, and idle pulleys 30 for directing the travel of the said belt in going to and coming from the said platen roll pulley to cause it to pass closely by the center line of the hinge axis of the said rocker shaft.

35 10. In a machine of the class described, an impression bed, an impression carriage mounted to be moved outward and back over the said impression bed, a shaft supported in the said impression carriage frame and extending across over the said bed and said 40 shaft mounted to be adjusted bodily in the frame of the said impression carriage, a platen roll carried by the said carriage and adapted to impress paper on the gelatin sheet on the said bed, a rocker shaft adapted to 45 support and raise and lower the said platen roll and said rocker shaft hinged in the frame of the said carriage, said adjustable shaft carrying a pulley and adapted to be driven by a gear and rack the latter being associated 50 with the said bed and a pulley on the said platen roll and said rocker having its hinge axis mounted in a position between the said platen roll and the said adjustable shaft, means for revolving the said platen roll and 55 for holding the same against revolution and connected to the said adjustable shaft.

60 11. In a machine of the class described, a frame adapted to hold an impression bed over which a gelatin sheet is trained in making copies, said frame having trackways on

each side and adapted to support an impression carriage that may be moved outward and back over the said impression bed, said trackways having curved portions extending downward at the front of the machine and 70 said impression carriage adapted to be moved in a downward position on the downward curved portions of said trackways, a margin bar hinged and supported in the said frame and adapted to register paper in position on the said impression bed, stops for arresting the carriage in registering position in relation to the said margin bar, means for adjusting said stops and moving the said margin bar to permit the said carriage to 75 travel down on the said curved trackways and for clearance for the admission of the end of the gelatin sheet.

80 12. In a machine of the class described, an impression bed, an impression carriage mounted to travel over the said bed in laying paper thereon, adjustable stops for registering the position of the said carriage in relation to the said bed, a margin bar hinged to the frame of the machine and adapted to register paper in relation to the said bed, mechanism for connecting the movement of the said adjustable stops and the movement of the said margin bar whereby they are simultaneously moved to clearance positions to 85 permit the carriage to be cleared of the impression bed for the entry of a fresh gelatin sheet.

90 13. In a machine of the class described, a frame adapted to support an impression bed, trackways on each side of the said bed and racks in association with the said trackways the teeth of the said racks having open spaces at the bottom of the teeth and bars located along the sides of the teeth for guiding laterally the teeth of gear wheels which gear wheels engage the said rack, an impression carriage mounted on the said trackways and provided with gear wheels which engage the said racks, said racks and trackways extending parallel along in association with the said impression bed and curved downward at the front of the machine beyond the region of the impression bed.

95 14. In a machine of the class described, a frame, an impression bed mounted on the frame, racks extending along the side of the said impression bed, an impression carriage mounted to travel outward and back over the said impression bed and said impression carriage mounted on shafts extending across the said impression bed, one of the said shafts adjustable in relation to the other longitudinally of the said bed, a platen roll mounted in the said carriage and adapted to be raised and lowered in relation to the said bed, a pulley on the shaft of the said platen roll and a pulley on one of the said shafts upon which the said impression carriage is moved and a belt connection from the last named pulley to and 100

driving the pulley on the said platen roll shaft.

15. In a machine of the class described, an impression carriage mounted to travel outward and back over an impression bed and said impression carriage having a cross shaft swingingly connected to the remainder of said carriage and extending the width of the carriage over an impression bed, and said shaft 5 adjustable in a longitudinal direction as relates to the impression bed by means of a rocker shaft having arms connected to blocks which carry the bearing which support the said shaft in relation to its adjustment and 10 the said blocks sliding in guideways in the said impression carriage.

16. In a machine of the class described, an impression bed, an impression carriage mounted to be moved outward and back over 20 the said bed, a platen roll carried by the said impression carriage and supported in arms of a rocker shaft, a rocker shaft hinged in the frame of the said impression carriage and mounted in open sided bearings in the said 25 frame and sliding cover plates adapted to cover and uncover the open sides of the said rocker shaft bearings whereby the rocker shaft may be taken out bodily from the carriage frame and carry with it the said platen 30 roll.

Signed at Chicago, in the county of Cook and State of Illinois this 17th day of July 1928.

WILLIAM ERASTUS WILLIAMS.
